CLAIM

The ornamental design for a clampable mousepad, substantially as shown and described.

DESCRIPTION

FIG. 1 is a perspective view of a clampable mousepad, showing our new design;

FIG. 2 is a top view thereof;

FIG. 3 is a bottom view thereof;

FIG. 4 is a front view thereof;

FIG. 5 is a rear view thereof;

FIG. 6 is a first side view thereof; and,

FIG. 7 is a second side view thereof.

Any features shown in broken lines form no part of the claimed design.

1 Claim, 7 Drawing Sheets
